UNITED STATES PATENT OFFICE.

ALFRED C. TRAPP, OF MILWAUKEE, WISCONSIN.

AUTOMATIC STABILIZING DEVICE.

Application filed September 12, 1923. Serial No. 662,241.

To all whom it may concern:

Be it known that I, ALFRED C. TRAPP, a citizen of the United States, and resident of Milwaukee, in the county of Milwaukee and 5 State of Wisconsin, have invented certain new and useful Improvements in Automatic Stabilizing Devices; and I do hereby declare that the following is a full, clear, and exact description thereof.

10 My invention relates to improvements in automatic stabilizing devices and is particularly directed to that class adapted for use upon ships, one embodiment of which is disclosed in Patent No. 1,416,911 issued to me 15 on the 23rd day of May 1922.

In my former patent I have provided a plurality of cargo carrying units which are adapted to be maintained in a level or stabilized position regardless of the pitch of 20 the vessel. In this structure it has been found that unless each unit is properly weighted its return to its normal position is somewhat retarded, and it is the object of this invention to provide means for returning the various units independently and collectively to their normal positions.

It is of course to be understood that my invention as described hereinafter is not only applicable for use upon ships, but may 30 be used as effectively upon aeroplanes, sleeping cars, or in fact for any device wherein it is desired to maintain an object or unit in a certain position.

In the accompanying drawings:—

35 Figure 1, is a side view, in elevation, of a ship, the hull of the same being broken away to disclose the structure of the supporting means for the various units.

Figure 2 is a sectional view taken on the 40 line 2—2 of Figure 1, and

Figure 3 is view taken on the line 3—3 of Figure 1.

Referring to the accompanying drawings, wherein like reference characters denote corresponding parts throughout the several views, the numeral 1 designates a boat constructed in any desired manner and provided with a hull 2. The hull 2 has extending transversely thereof and adjacent its ends bulk-heads 3 and 4.

50 Fitted within the hull 2 is a rectangular frame 5 composed of the side walls 6 and the end walls 7, the latter having made integral therewith trunnions 8 which are mounted for oscillation upon a roller race 9 formed in the intermediate portion of each bulk-head. The

end portion of each trunnion has detachably secured thereto, by the bolts 10, a plate 11 which prevents any longitudinal movement of the trunnions within the bulk-heads, and 60 further serves as a retainer for the rollers forming the race 9. Referring to Figure 3 it will be noted that the side walls 6 of the frame 5 follow closely the outlines of the sides of the hull.

65 The frame 5 has placed therein a plurality of cargo carrying units 12, each of which has formed integral therewith and on its side walls, trunnions 13 which pass through suitable openings within the side walls 6, and each trunnion is adapted to ride upon a roller race 14 fitted within each opening, in a manner similar to that previously described. As in the former use of this structure the trunnions 13 have secured to their end portions a plate 15.

70 Usually in structure of the character just described the weight of the cargo within each unit is depended upon to maintain the same in a level or stabilized position, but in 75 this invention it is my purpose to provide means for performing this function in the event that the units cannot stabilize themselves, and in order to do this I have secured to the plate 11, connected to each trunnion 80 upon which the frame 5 is supported an eye 16 the same having secured therein the end portions of flexible cables 17 which are passed over suitable rollers 18 mounted upon the outer face of each bulkhead. Each cable 90 17 has connected thereto at its free end a weight 19, the purpose of which is to assist in the return of the frame to its level or stabilized position.

95 In a like manner I have secured to the plates 15, secured to the trunnions of each unit 12, similar means for maintaining each unit in a level or stabilized position, and as disclosed in Figure 1 this means consists of the weights 20 secured to each plate 15 by 100 means of the flexible cables 21 which pass over rollers 22 mounted upon the side walls of the frame.

105 In the operation of a ship having thereon my improved stabilizing device, there will be no motion of the hull for which the units 12 cannot automatically maintain themselves in a level or stabilized position. When the hull is pitching longitudinally, each unit will swing upon its supporting trunnions 110 and when the hull is rolling from side to side the units 12 will all move together upon

the longitudinal axes of the frame 5 supported by the trunnions 8. In each swing of the units or the frame by which they are supported, the weights connected thereto 5 will assist in maintaining the elements in a level position.

From the foregoing, it is thought that the construction, operation and many advantages of the herein-described invention will 10 be apparent to those skilled in the art, without further description, and it will be understood that various changes in the size, shape, proportion, and minor details of construction may be resorted to without deviating from the spirit or sacrificing any of the advantages of the invention.

Having thus fully described my invention, what I claim as new, and desire to secure by Letters Patent, is:—
20 1. A ship provided with a hull having pivoted longitudinally thereof a frame, cargo carrying units pivoted transversely of said frame, said units adapted to swing with and independently of said frame, and means 25 connected to the frame and each unit and carried by its respective supporting element for maintaining the same in a level position.

2. A ship provided with a hull having 30 pivoted longitudinally thereof a frame, a plurality of cargo units pivoted transversely of said frame, said frame and units adapted to swing upon their pivots, and weights connected adjacent the pivot point of each 35 unit and frame and carried by its respective supporting element for maintaining the same in a level position.

3. A ship provided with a hull having

pivoted longitudinally thereof a frame and a plurality of cargo units pivoted transversely of said frame, said frame and units adapted to swing upon their pivots, weights connected to each unit and frame and carried by the supporting member therefor, for maintaining the same in a level position. 40

4. A ship provided with a hull having pivoted longitudinally thereof a frame, a plurality of cargo units pivoted transversely of said frame, roller bearings at each pivot point, said frame and units adapted to swing upon their pivots, weights connected to each unit and frame and carried by the supporting member therefor, for maintaining the unit or frame in a level position. 45

5. A stabilizer of the class described comprising a main frame pivoted longitudinally of a carrier, a plurality of units pivoted to said frame, and weights connected adjacent the pivot point of each unit and frame for maintaining the same in a level position. 50

6. A ship provided with a hull portion having pivoted longitudinally thereof a frame, cargo carrying units pivoted transversely of said frame, means connected to each of said units adjacent its pivot point and carried by said frame for maintaining said units in a level position, and said frame having similar means connected to its end portions adjacent its pivots and carried by its supporting element for maintaining said frame in a level position. 65

In testimony that I claim the foregoing I have hereunto set my hand at Milwaukee, in the county of Milwaukee and State of Wisconsin.

ALFRED C. TRAPP.
